STOVEPIPE

Franklin R. Jackes, Ladue, and Sam Strano, St. Louis, Mo., assignors to Jackes-Evans Manufacturing Company, St. Louis, Mo., a corporation of Missouri

Application March 6, 1944, Serial No. 525,224

4 Claims. (Cl. 138—70)

This invention relates to stove pipe, and with regard to certain more specific features to stove pipe formed from cold-rolled steel sheets or the like.

Among the several objects of the invention may be noted the provision of means for improving the appearance of stove pipe by a structural shape which reflects incident light in such a manner as to distract attention from inherent surface blemishes in the ordinary finish used for such pipe; the provision of a structural shape of the class described which also improves the heating surface, and strength of the pipe; and which makes pipe joints between sections more reliable; and the provision of such means which will allow of shipment of pipe sections in substantially flat stacked condition, if desired, as distinguished from the substantially cylindric nested condition now employed, thus saving shipping expense, particularly for export. Other objects will be in part obvious and in part pointed out hereinafter.

The invention accordingly comprises the elements and combinations of elements, features of construction, and arrangements of parts which will be exemplified in the structures hereinafter described, and the scope of the application of which will be indicated in the following claims.

In the accompanying drawing, in which are illustrated two of various possible embodiments of the invention,

Fig. 1 is a developed flat sheet showing a first step;

Fig. 2 is a perspective view of the sheet of Fig. 1 shown lightly curled for substantially flat stacked export shipment;

Fig. 3 is a side elevation of a straight length of stove pipe embodying the invention;

Fig. 4 is a diagrammatic horizontal section taken on line 4—4 of Fig. 3;

Fig. 5 is a fragmentary enlarged detailed section of a part of Fig. 4; and,

Fig. 6 shows the assembly of a straight length of pipe and elbow, the latter also being made according to the invention.

Figs. 1-4 and 6 are on reduced scale. Fig. 5 shows substantially the proper relationship between pitch of corrugations and radius of curvature.

Similar reference characters indicate corresponding parts throughout the several views of the drawing.

Stove pipe is commercially made from sheet segments cut from a continuous web of cold-rolled, thin sheet steel. The grain of the steel is longitudinal with respect to the length of the

continuous web and the sheets are cut from the web so that their dimensions, which later become the lengths of pipe sections, are crosswise with respect to the web. This places the grain of the sheet metal stock girthwise of the resulting pipe. This arrangement is mechanically desirable because it places the grain at right angles to the edgewise lock-seam components which might crack during their formation, if the grain were parallel to the pipe length. The segments, after the seam components and the usual end swaging bulges have been made, are given a fairly shiny finish which it is intended shall provide a good appearance in the final pipe. However, the above-mentioned grain causes some variations in the finish where it follows the grain. The grain toward the edges of the original web of steel is often different from the grain at the center and the result is that the ultimate pipe sections sometimes have variations of finish along their lengths which is undesirable in any string of pipe sections. Furthermore, by the time that a pipe section has been formed and the lock-seams closed by the user, the surface has received marks and other blemishes. The invention at small cost provides means for rendering innocuous to the eye all or most of the above-mentioned blemishes and gives a pleasing continuous streamlined appearance to a pipe section or string of pipe sections as finally set up.

The above ends are accomplished with added structural advantages. Ordinarily the sheet segments above-mentioned are precurled substantially into cylinders and shipped in nested groups. This is so that when sections are locked at their seams to form the ultimate pipe, the pipe will be round, instead of some odd section which occurs if attempts are made to roll up from flat segments. Thus shipment of the stock must ordinarily be of nested, almost completely curled sections. If these could be shipped substantially flat, particularly in the export trade, a considerable saving would be effected in the volumes of large shipments. The present invention makes the hand formation (by the user) of round pipe, as reliable from substantially flat sheets, as it was heretofore from more completely curled lengths.

Other desirable advantages of solving the appearance problem by the means herein described are that it also provides a better joint between sections.

Referring now more particularly to Fig. 1, numeral 1 indicates a cold-rolled sheet blank, the grain of which extends crosswise of the figure from left to right. The grain does not show on

the drawing. On the edges of this blank are the edgewise male and female lock joint components 3 and 5 respectively which, after the blank is curled up may be interlocked to form a seam 6. Joining of the seam components is done by the user. The character of the locking element constituted by the components 3 and 5 is well known and further description is unnecessary herein. Any of various types may be used and they per se do not constitute the invention.

An important feature of the invention is the special fine-pitch corrugated formation of the sheet parallel to the locking elements 3 and 5, as shown at numeral 7. These corrugations are straight and regularly spaced and are constituted by relatively flat longitudinal surfaces 9 joined at straight, longitudinal intersections 44. The circumferential pitch distance P between intersection lines 44 is at least several times the radial height h of the corrugations.

As indicated in Fig. 5, the diametral pitch of the corrugations is of the order of 20. The term diametral pitch is herein to be taken in its usual sense of a certain number of corrugations or circular pitch distances per inch of mean pipe diameter. It is of course to be understood that this requirement of 20 d. p. needs to be met only approximately and may be taken down as low as 15 d. p. It may also be increased above 20, but a limit is soon reached due to mechanical limitations in making fine-pitch corrugations.

The result is a series of long, thin, flat, plane strips formed in the pipe at sharp angles to one another, which present elongate, facet-like surface stripes some of which reflect light at certain angles, and others of which do not, thus giving the pipe an appearance of being sharply striped (see Fig. 3). What particular strips reflect and what ones do not, depends upon the incident light, but the differential effect occurs in any ordinary light. This longitudinal stripe effect is so pronounced that any blemishes on the outside surface, due to variations in finish due to grain, blotching, or handling are not noticed at all by the eye. In fact, this effect is so pronounced that when the pipe embodying the invention is placed next to a pipe without it, both having the same surface finish, the latter by comparison appears to be somewhat defective. Thus the invention provides a much improved and consistently good appearance without the care necessary to prevent surface blemishes.

At numeral 43 in Fig. 2 is shown a swaged portion which in the finished pipe limits the telescoping between ends of adjacent sections. This is directed outward on the finished pipe. At the time that the swage 43 is inserted, the blanks are given a slight bow as shown in Fig. 2. This is for substantially flat export shipment. The bow is inserted by suitable rolls. If desired, complete curling may be effected such as is ordinarily used for domestic shipments. This would provide a substantially complete cylinder with unlocked seams adapted to be nested for domestic shipment and final seam closure by the user. The invention is advantageous because the material required for the swage 43 may be robbed from the corrugations, instead of from adjacent parts of the pipe. Formerly the pipe had substantial constrictions adjacent each swage portion because of this robbing effect; whereas the pipe of the invention does not need to have these constrictions to any substantial extent. However, if desired a swage may be used having a constriction.

It is to be understood that the corrugations in

5 collar 8 beyond swage 43 are crimped slightly more than those in the balance of the section. Thus when a pipe is formed as shown in Fig. 3 by rolling up the Fig. 2 blank and interlocking the lock 3 and 5, one end of a section will slip into the opposite end on the adjacent section. Heretofore slight corrugations have been used at the male end of the telescopic end of a section but the female end on an adjacent section was uncorrugated. By means of the present invention there is a resilient meshing or interlocking effect between two sets of corrugations at each joint between sections. At the same time an elastic grip is provided which makes the resulting joint tighter.

10 It will be seen that the blank of Fig. 2 is substantially flat, though slightly bowed. When the pipe of Fig. 3 is formed up from this Fig. 2 form it is accurately round as shown in Figs. 3 and 4 without effort being taken by the assembler to 15 form it so. In other words the stresses are so distributed by the corrugations, despite the peripheral grain that a round result is automatically assured. Heretofore substantially flat sheets even when bowed somewhat could not be so used. This 20 was particularly true in the case of peripherally grained pipe. It was necessary for the manufacturer to curl the blank permanently to almost a cylindric shape. By means of the present invention the peripheral grain is so broken up by the narrow longitudinal corrugations that a true 25 circular effect is easily obtained upon rolling up the sheet. Thus the present invention allows the manufacture of corrugated substantially flat segments instead of in the old cylindric form. It is 30 to be understood however that the invention may be made for shipment in old cylindric form if desired instead of in the substantially flat form of Fig. 2. For small domestic shipments the shipping cost saving in favor of the Fig. 2 form is not so great, but for export shipments it is great.

The corrugations 9, 44 may be placed in the Fig. 1 metal blank by means of rollers which are operative before any of the other elements 3, 5 or 43 are formed.

35 Fig. 6 shows a straight length of pipe S telescoped at its left-end with an elbow L. This elbow also carries similar corrugations 45 which follow the curve of the elbow. These corrugations are placed in the rectangular blank from 40 which the elbow is made before this blank is otherwise processed. After the corrugations 45 have been inserted into the blank, a cylinder is made. Then the usual deep, rounded peripheral corrugations 47 are inserted at 90 degrees (isoclimal) to the corrugations 45. Corrugations 47 are deep and allow of the usual outside stretch and bending of the cylinder to form the elbow as indicated. In other words, the deep-peripheral corrugations 47 act in the usual way as a bellows, 45 allowing bending of the cylinder from which the elbow is made. During the bending process, the previously applied corrugations 45 become curved as indicated. As shown in the drawing, the appearance of the corrugations 45 traversing the corrugations 47 is that of extensions of the corrugations 9, 44 in the adjacent straight pipe section. Wherever the corrugations 45 and 47 cross, their tangents are perpendicular. No swaged portions are necessary on the elbow since 50 the endwise members of corrugations 47 form a limit to telescoping in the absence of a swage 43 on an adjacent female section-end. In Fig. 6 a swage 43 on an adjacent section-end limits telescoping.

55 An added advantage of the invention is that

the heating surface of the pipe is increased, and since the ordinary stove pipe has about two times the heating surface of the stove with which it is connected, the gain is substantial.

It should be noted that the shallow depth of the corrugations 9 and 15 prevent undue stretching at the telescoping joints between sections, such as would be the case with deep corrugations.

Since the corrugation of a substantially flat sheet which is shown in Fig. 2 results in imparting to the sheet the property of its automatically assuming a circular form when rolled up to form a stove pipe, the intermediate product such as shown in Fig. 2 is of importance.

In view of the above, it will be seen that the several objects of the invention are achieved and other advantageous results attained.

As many changes could be made in the above constructions without departing from the scope of the invention, it is intended that all matter contained in the above description or shown in the accompanying drawing shall be interpreted as illustrative and not in a limiting sense.

We claim:

1. A stove pipe comprising a flexible metal sheet adapted readily to be bent into a substantially true circle by manual means only, said sheet having relatively narrow longitudinal corrugations therein of diametral pitch of the order of not less than 15.

2. A stove pipe comprising a flexible metal

sheet adapted readily to be bent into a substantially true circle by manual means only, said sheet having relatively narrow longitudinal corrugations therein of diametral pitch of not less than 15, the inherent grain of the metal sheet being peripherally disposed and substantially at right angles to said corrugations.

3. A stove pipe comprising a flexible metal sheet adapted readily to be bent into a substantially true circle by manual means only, said sheet having longitudinal corrugations therein of diametral pitch of the order of not less than 15, said corrugations each consisting of two elongate flat areas angularly connected, the circular pitch distances between corrugations being substantially greater than the radial depths thereof.

4. A stove pipe comprising a flexible metal sheet adapted readily to be bent into a substantially true circle by manual means only, said sheet having narrow longitudinal corrugations therein of diametral pitch of the order of not less than 15, said corrugations each consisting of two elongate flat areas angularly connected, the circular pitch distances between corrugations being substantially greater than the radial depth thereof, and the inherent grain of the metal sheet being peripherally disposed and substantially at right angles to said corrugations.
